US00D573965S

(12) **United States Design Patent**
Choi et al.

(10) **Patent No.:** US D573,965 S
(45) **Date of Patent:** ** Jul. 29, 2008

(54) **PORTABLE PHONE**

(75) Inventors: **Hyok Su Choi**, Yongin-si (KR);
Yoon-Young Cho, Seoul (KR);
Chang-Soo Lee, Incheon (KR)

(73) Assignee: **Samsung Electronics Co., Ltd.**,
Suwon-si (KR)

(**) Term: **14 Years**

(21) Appl. No.: **29/274,093**

(22) Filed: **Mar. 28, 2007**

(30) **Foreign Application Priority Data**

Oct. 31, 2006 (KR) 30-2006-0043403

(51) **LOC (8) Cl.** 14-03

(52) **U.S. Cl.** D14/138
